Benjamin Winkley,
Letters Patent.

The Schedule referred to in these Letters Patent and making part of the same containing a description in the words of the said Benjamin Winkley himself of his improvement in the machine for glazing Windows on the columns & pillars.

This machine is sustained by a frame of the following construction viz. two sills of suitable timber, two and a half feet long, and 3 by 4 inches square, in each of these sills set the feet of two posts, which are three feet high, made of joists of suitable timber three inches square and thus form the ends of the frame. The sides are connected by two girths, that are framed into the posts, the upper edge of the girths being about one foot below the top of the posts, the intermediate space between the girths being two and a half inches. The machine consists of two head blocks, one of which is fastened on the top of the posts, in one end, projecting two and a half inches, over the outside of the posts, and the ends, projecting equal distances from the sides of the frame. The other head block is moveable, and consists of a plank placed in a vertical position between the girths, with suitable shoulders to the same resting on the upper side of the girths, and on the upper end of this is framed a block of timber of the same dimensions as the head block, stationed on the upper ends of the posts, at the other end of the frame. In each of the head blocks, which are two feet long is cut a mortise entirely through the blocks about eighteen inches long & one inch wide. To each of these head blocks belongs a cap piece two & a half inches thick and 3 inches wide, the which have mortises corresponding with those before mentioned. The blocks and cap pieces are perforated through between the mortises and the ends, and to these perforations screws are fitted of a convenient size made of wood or iron or some other suitable material with nuts suited to the same. Between the head blocks is a moveable vice composed of a block of timber about 20 inches long and 3 by 4 inches square, from which a stem passes below, between the girths, and a key works thro' the stem at the underside of the girths. In this block are two mortises about nine inches apart, and in these mortises are set the ends of two pieces of timber about 14 inches long and 2 by 3 inches square. The upper ends of these are curved, the concave sides laying

inwards to receive the column or pillar to be veneered, and thro this a screw passes by which the columns are fastened together. in one end of the vice block is a piece of timber placed vertically and extending upward about 3 feet in the upper end of which is a pulley, on the same side of the machine is a lever five feet in length, one end of which is attached to a post of the machine, and a weight of sufficient heft attached to the other end, to keep the wrapper fast. a cord attached to the lever passes over the above mentioned pulley and the end is confined to a wrap for which is a piece of canvas cloth glazed over with bees wax, the wrapper to be two inches longer and about six inches wider than the veneer. the end of the wrapper to which the cord is confined is suspended by a piece of board about 3 inches wide. the column is prepared by cutting a groove in one side from end to end large enough to receive one edge of the wrapper and fitting one end to the mortise in a crank or lever to be used in the operation. two columns are then placed on the head block, when they are confined by screwing the cap pieces down, on the upper sides and entering suitable keys thro the mortises in the cap pieces and blocks and screwing up the vice in the middle of the columns. The lower end of the wrapper is fastened in the groove in one column by gluing and the veneer to be used is placed on the column so as to bring the edge of the veneer in contact with the wrapper. By affixing the crank or lever to the end of the column to be veneered and turning the same inward the veneer is drawn in between the wrapper and column and being pressed close as it passes between the columns is duly fitted in the work. the glue is applied as the column turns. the column remains in the machine until the glue is dry and is then disengaged by cutting the wrapper at the groove, when another column is placed in the machine and the operation is repeated. The size of the machine may be varied so as to be adapted to the columns of any convenient size.
